UNITED STATES PATENT OFFICE.

JOHN REICHERT, OF RACINE, WISCONSIN.

HAME AND TRACE CONNECTION.

1,254,275.

Specification of Letters Patent. Patented Jan. 22, 1918.

Application filed July 21, 1910. Serial No. 573,129.

To all whom it may concern:

Be it known that I, JOHN REICHERT, a citizen of the United States, residing at Racine, Racine county, Wisconsin, have invented 5 certain new and useful Improvements in Hame and Trace Connections; and I do hereby declare the following to be a full, clear, and exact description of the invention, such as will enable others skilled in the art to 10 which it appertains to make and use the same.

This invention relates to certain improvements in hame clips; and the objects and nature of the invention will be readily understood by those skilled in the art in the light 15 of the following explanation of the accompanying drawings which show what I now consider my preferred embodiment.

The invention consists in certain novel 20 features in construction and in arrangements and combinations as more fully and particularly set forth and specified hereinafter.

Referring to the accompanying drawings;

Figure 1, is a side elevation of portions of 25 a bolt-hame and a trace together with the connection of my invention between the trace and hame.

Fig. 2, is a longitudinal vertical sectional view of the trace clip, the hame staple clip, 30 and the swivel loop, a portion of a hame staple being shown.

Fig. 3, is a longitudinal horizontal section on the line 3—3, Fig. 1.

Fig. 4, is a detail perspective view of a 35 hame staple clip, the swivel loop, and the connecting rivet, the parts being shown separated.

Fig. 5, is a detail perspective view of the 40 trace clip, before application.

Fig. 6, is a detail longitudinal section 45 through the bolt clip showing the same slightly bulged to receive a roller or bushing surrounding the hame bolt.

In the drawings, 1, is any suitable hame, 50 which can have the removable bolt 10, of Fig. 1, or the fixed staple 11, of Fig. 2, or the removable bolt 10 of Fig. 6, surrounded by loose bushing, sleeve or roller, as will be well understood by those skilled in the art.

2, is the hame connection (bolt or staple) 55 clip. This clip 2, is bent from suitable sheet steel into U-shape to form the vertically elongated rounded bearing portion 20, receiving and passing behind the hame bolt or staple and free to rock or oscillate thereon as an axis, and having the flat parallel

rearwardly extending ends or ears centrally or transversely perforated to receive the rivet on which the swivel eye or loop rocks. The vertically swingable swivel eye or loop 60 is usually formed by a single casting or forging consisting of the rear end loop 32, and the disk-like front head 3, approximately circular in form and having a flat edge or periphery 30, and parallel flat side faces and 65 a central transverse bearing opening 31, forming the center of the radius of the curved bearing edge 30. The loop 32 is formed with a transverse opening and a rear-end vertical journal bar. 70

4, is a heavy rivet on which the swivel eye or loop rocks vertically and by which it is confined to the hame-bolt clip. This rivet passes through the rearwardly extending parallel ends of the clip 2, and is upset thereon and fixed thereto and passes loosely through the bearing opening 31, of the swivel eye. The leather (or other suitable material) trace 5, is provided with an end clip 6, loosely coupling the same to the rearwardly projecting loop 32, of the swivel eye. This clip 6, consists of an elongated strip of sheet steel (or other suitable material) bent into U-shape to form the elongated parallel ends between which the trace end fits and to 85 which it is firmly riveted or otherwise secured, while the front or doubled end 60, of the clip is rounded to form a bearing surface passing around and bearing against and oscillatory on the vertical bar of the loop 32. 90

One side or end portion of this clip 6, has a longitudinally disposed U-shaped cut therethrough midway the vertical width of the clip and extending rearwardly from the flat side with the two separated ends of the 95 cut terminating about at the front of the doubled or rounded bearing end of the clip, and forming a longitudinally disposed rearwardly extending tongue or finger 61, located midway the vertical width of the clip 100 and extending rearwardly from the rounded front end of the clip. This tongue is adapted to have its rear free end bent or punched inwardly to pass in rear of and fit and partially embrace the vertical bar of the loop 105 32, and thereby hold the clip against forward movement thereon while permitting the clip to freely rock horizontally on said bar. The leather trace end fits up against this tongue and is thereby held from wearing engagement with the bar of the loop 32. 110 This tongue 61 is preferably located in the

inner side of the clip, that is, the side next to the draft animal, and material advantages are attained by employing the single intermediate finger arranged about at the center 5 of the swivel loop bar and about at the center of the trace clip, as the clip is not weakened by forming the tongue therein while its wearing qualities are increased; the tongue is strengthened and braced by the 10 material of the clip both above and below the tongue; the opening formed by bending in the tongue is closed by the trace end; and the tongue being practically inclosed within the device does not afford projections etc. to catch the mane of the draft animal. These trace clips can be produced for the market as shown in Fig. 5, for application to hame bolts or staples or other hame connections such as swivel eyes, and 15 to receive traces as heretofore described.

The hame bolt-or-staple clips are economically bent up from sheet steel or the like and are preferably imperforate except for the perforations to receive rivets 4, and have 20 vertically wide or long bearing portions 20, extending the full lengths of the hame bolts or staples. These clips are easily clipped around the hame bolts or staples and the swivel eyes are readily applied thereto to 25 receive the securing rivets 4. The curved edge surface 30, of the swivel eye is concentric with the rivet and bears against the 30

hame bolt or staple (about at the center of its length) and thus holds the clip thereto against rattling and looseness and forms a 35 most simple and efficient structure wherein wear is reduced to the minimum.

The device can be easily removed by merely driving out the rivet 4, and then separating the parts, and can be as easily applied by using a new rivet or the old rivet 40 if not unduly damaged.

What I claim is:—

A trace connection comprising a U-shaped metal clip having a rounded front bearing 45 end 60, and rearwardly extending elongated approximately parallel sides, said clip between its longitudinal edges formed with an approximately U-shaped longitudinal cut in one side and extending into said bearing 50 end and forming an intermediate finger 61, said finger being bent inwardly behind said bearing end to form a rear stop and bearing portion, and to lock the clip to the bar or member to which it is applied, the side opening 55 formed by bending said finger inwardly adapted to be closed by the trace secured in said clip.

In testimony whereof I affix my signature in presence of two witnesses.

JOHN REICHERT.
